UNITED STATES PATENT OFFICE.

LYMAN NICHOLS, OF TRENTON, NEW JERSEY.

DESIGN FOR A SINK-LEG.

SPECIFICATION forming part of Design No. 24,881, dated November 12, 1895.

Application filed June 21, 1895. Serial No. 553,610. Term of patent 14 years.

To all whom it may concern:

Be it known that I, LYMAN NICHOLS, of Trenton, New Jersey, have invented and produced a new and original Design for or Configuration of the Supports or Legs for Sinks and other Uses, of which the following is a description, referring to the accompanying drawings, which form a part of this specification.

10 The sink support or leg is designed to be set cornerwise at the corners of the sink.

Figure 1 is a side elevation of a leg or support, showing my design. Fig. 2 is a front elevation of the same. Fig. 3 is a plan view, 15 and Fig. 4 is a cross-section on the plane 4-4 of Figs. 1 and 2.

These four views are deemed necessary to fully illustrate my design or configuration, and throughout the figures like letters of reference indicate like parts, features, or ornamentation.

In Fig. 1 I have shown in dotted lines a sink and the attachment for holding the leg in place when in use, the sink being indicated 25 by S and the attachment or frame by F. For convenience of illustration I have shown the sink in side elevation, though as the leg is intended to be set cornerwise upon the sink, as clearly indicated by the dotted lines in Fig.

30 3, Fig. 1 is not strictly accurate, since the leg would appear in three-quarters view if set cornerwise at the corner of the sink; but in order to show the conformation of the leg more directly and simply I have shown it in side view in Fig. 1.

The upper part of the support presents the flat surface P, upon which the object to be supported may rest. At the forward part

this turns up and terminates in the ornamental portion or part R, constituting the corner-piece.

The vertical portion or leg proper L extends downward in the gradually - tapered and slightly curvilinear form shown in the figures, the curve, as seen from the front, being first 45 convex and then concave, terminating in the ornamental foot or base V. A bead or small flange B runs down the leg for the greater part of its length from the top.

While in its more complete aspect my design comprises all the features that I have named, there are certain individual features to which I attribute some importance quite independent of the others. Among these are, first, the upturned beaded corner portion R; 55 second, the leg proper with the bead B at the rear and presenting the cross-section shown in Fig. 4, but tapering and terminating in a smaller and differently-shaped cross-section toward the foot, which may be rounded or 60 oval, and, third, the claw-foot V in combination with the corner portion R, to which it is peculiarly suited, as may be seen in Figs. 1 and 2.

Having in the foregoing fully set forth my 65 design, I claim and desire to secure by these Letters Patent the following:

The design for a sink support or leg, substantially as herein set forth and illustrated.

In testimony whereof I have hereunto set 70 my hand, at Trenton, New Jersey, this 28th day of February, A. D. 1895.

LYMAN NICHOLS.
